UNITED STATES PATENT OFFICE

JAMES KANTOR, OF CHICAGO, ILLINOIS, ASSIGNOR TO THE LIQUID CARBONIC CORPORATION, OF CHICAGO, ILLINOIS

FILLING MECHANISM

Application filed March 28, 1927. Serial No. 179,084.

My invention relates to improvements in filling mechanisms of the type which are adapted to dispose measured amounts of liquid, such as syrup, in bottles, and it consists in the combinations, constructions, and arrangements herein described and claimed.

An object of my invention is to provide a filling mechanism in which the capacity of the measuring means may be varied to the slightest fraction of an ounce.

10 A further object of my invention is to provide a device of the type described in which the members of the measuring means may be moved simultaneously for varying the capacity of the measuring cup.

15 A further object of my invention is to provide a device of the type described by means of which the capacity of the measuring cup may be varied at a relatively great speed.

20 A further object of my invention is to provide a device of the type described by means of which desired quantities of the liquid may be disposed in each bottle, irrespective of the temperature effect upon the liquid or the 25 density of the liquid used.

Other objects and advantages will appear in the following specification, and the novel features of the invention will be particularly pointed out in the appended claims.

30 My invention is illustrated in the accompanying drawings, forming part of this application, in which

Figure 1 is a side sectional view of my device, portions thereof being shown in elevation.

Figure 2 is a plan view of my device, and

Figure 3 is a section along the line 3-3 of Figure 1.

In carrying out my invention, I provide a 40 liquid tank 1 having one or more openings 2 in the bottom 3 thereof. A guide or support rod 4 is slidably disposed in a bushing 5 which extends through the bottom 3 of the tank 1. A bell 6 for receiving the neck of a 45 bottle which is indicated at 7 is rigidly mounted upon the lower end of the guide rod 4. A compression spring 8 is disposed concentric with the guide rod 4 and bears at one end upon the bell portion 6 and at the other 50 end upon the bushing 5. A support 9 is se-

cured to the upper end of the guide rod 4 by means of a nut 10.

A measuring cup which is composed of a cylindrical body portion 11 and a bottom portion 12 is disposed in the tank 1. The 55 measuring cup is so constructed that the cylindrical body portion 11 may be moved with respect to the bottom portion 12 and still prevent a liquid from passing from the cup between the body portion 11 and the bottom 60 portion 12. A bushing 13 is provided for the bottom portion 12. The inner wall of the bottom portion 12 tapers inwardly and downwardly to a point adjacent the bushing 13. The tank 1 is provided with a liquid 14 which 65 maintains a level shown in Figure 1, by means not shown. A liquid valve tube 15 extends through the bell 6, through the opening 2, and through the bushing 13 to a point above the level of the liquid 14.

The body portion 11 is provided with a hollow sleeve or tube 16 which is secured at one end thereto. The other end of the sleeve 16 extends upwardly and is provided with an arm 17 which extends outwardly at right 70 angles therefrom. A threaded shank 18 is secured to the arm 17 and extends upwardly therefrom. A drive gear 19 extends through the support 9 and is provided with an internally threaded portion 20 which is adapted to 75 receive the threaded shank 18. A relatively small gear 21 is rigidly mounted upon the drive gear 19.

The bottom portion 12 is provided with an annular recess 22 which is adapted to receive 80 a fork 23. An adjusting rod 24 is secured at one end to the fork 23 and extends upwardly through the sleeve 16 and is adapted to be moved with respect to the sleeve. The upper 85 end of the rod 24 is provided with threads 25. A driven gear 26 extends through an opening in the support 9 and is in mesh with the drive gear 19. The driven gear 26 is provided with an internally threaded portion 27 which is adapted to receive the threaded portion 25 of the adjusting rod 24. A reduced 90 portion 28 is provided on the driven gear 26 for receiving a relatively large indicating gear 29. The indicating gear 29 is in mesh 95 with the relatively small gear 21 and is held 100

in place by a washer 30 and a screw 31. The ratio of the gears 21 and 29 is 1 to 6. The indicating gear 29 is divided into three equal parts starting at the point indicated at 32 and bearing the marking 1 on one side and the marking 4 on the other side thereof. Numerals 2 and 3 are positioned adjacent the other dividing points. These parts are also divided into a number of equal parts. An indicating point 33 is mounted upon the support 9 and extends to a point substantially adjacent the periphery of the gear 29.

Gear-retaining flanges 34 and 35 are provided with semi-circular portions 36 and 37 which are receivable in annular grooves 38 and 39 of the gears 26 and 19 respectively. The retaining flanges 34 and 35 are removably secured to the support 9 by screws 40 and 41 respectively.

20 A drip check valve 42 is adjustably secured to the support 9 by a bar 43 and a screw 44. The drip check 42 is disposed in alignment with the liquid valve tube and adapted to engage with the upper end of the liquid valve tube when the drip check is in its lowermost position.

From the foregoing description of the various parts of the device, the operation thereof may be readily understood. As stated heretofore, the liquid 14 maintains approximately the level shown in Figure 1, irrespective of the speed at which the liquid passes from the tank.

35 The capacity of the measuring cup is from one to four ounces. However, the measuring cup may be so adjusted to hold a fraction less than one ounce or a fraction more than four ounces, if so desired.

Let us assume that the operator wishes to place four ounces of the liquid 14 into the bottle 7. The measuring cup, as shown in Figures 1 and 2, is set to receive just four ounces of the liquid. As the bottle 7 is moved upwardly, by means not shown, the bottle engages with the bell 6, thus raising the bell, the guide rod 4, the support 9, and the measuring cup upwardly to a point where the upper extremity of the measuring cup will be positioned above the level of the liquid 14. During this upward movement of the measuring cup, the full capacity which is four ounces of the liquid will be received in the measuring cup. When the measuring cup has reached its uppermost position, the drip check 42 will have been raised from the liquid valve tube 15 and the upper extremity of the liquid valve tube will be adjacent the lower portion of the tapering surface of the bottom portion 12. This allows the liquid which has been retained in the measuring cup to flow downwardly through the liquid valve tube 15 into the bottle 7. The tapering surface of the bottom portion 12 aids the liquid 65 in its travel toward the tube 15 and permits

all the liquid in the measuring cup to pass therefrom in a given time.

As the bottle 7 moves downwardly, the measuring cup is also moved downwardly by the force of the compression spring 8, and the drip check 42 engages with the upper end of the liquid valve tube 15 for preventing any liquid which should remain in the tube from passing therefrom until another bottle is brought into alignment with the tube. The drip check 42 is essential when the device is used in a low surrounding temperature or with a heavy liquid for holding all the liquid over the predetermined amount which is received in the measuring cup.

In filling machines of this type, a certain length of time is given for the passing of the liquid from the measuring cup into the bottle. This time remains the same, irrespective of the surrounding temperature or the specific gravity of the syrup. As for instance, a liquid, such as a syrup, will flow at a slower rate of speed during a relatively low surrounding temperature than when the surrounding temperature is relatively high. Some syrups or liquids owing to their density require more time to flow from the measuring cup into the bottle than do others. To allow for the slowness of the flow of liquid during a relatively low temperature or with the use of a relatively heavy syrup, the body portion 11 and the bottom portion 12 may be moved simultaneously with respect to each other.

The simultaneous movement of the bottom portion 12 and the body portion 11 with respect to each other is effected by rotating the gear 19. Let us assume that the operator wishes to reduce the capacity of the measuring cup to three ounces. By rotating the gear 19 in a counter-clockwise direction, see Figure 2, the shank 18 will be moved downwardly, thus moving the sleeve 16 with respect to the adjusting rod 24 and moving the body portion 11 with respect to the bottom portion 12. During the rotation of the gear 19 in a counter-clockwise direction, the gear 26 will be rotated in a clockwise direction, thus causing the adjusting rod 24 to move upwardly within the threaded opening 27. During the upward movement of the adjusting rod 24, the bottom portion 12 together with the fork 23 will be moved upwardly with respect to the body portion 11. In this manner, the body portion 11 and the bottom portion 12 are moved simultaneously with respect to each other. To change the capacity of the measuring cup from four ounces to three ounces, it is necessary to rotate the gear 19 two revolutions. During the revolving of the gear 19, the gear 21 will rotate the indicating gear 29 until the line bearing the numeral 3 thereupon is in registration with the indicating point 33. Continued rotation of the drive gear 19 and the relatively small gear 21 will

decrease the capacity of the measuring cup in accordance with the markings upon the indicating gear 29 as they align with the indicating point 33. It is obvious that with the simultaneous movement of the body portion 11 with respect to the bottom portion 12, the capacity of the measuring cup may be varied to the desired capacity in a short length of time.

10 I claim:

1. A device of the type described comprising a tank adapted to hold a liquid, said liquid maintaining a predetermined level in said tank, a liquid valve tube rigidly secured to said tank and having one end extending into said tank to a point above the level of said liquid, the other end of said liquid valve tube being adapted to enter a bottle, a measuring cup disposed concentric with said liquid valve tube in said tank, said measuring cup comprising a cylindrical body portion and a tapering bottom portion, a support, a drive gear, means operatively connecting said cylindrical body portion with said drive gear, a driven gear in mesh with said drive gear, means operatively connecting said bottom portion with said driven gear, an indicating gear carried by said driven gear and rotatable with respect thereto, an indicating point carried by said support and disposed adjacent the peripheral edge of said indicating gear, and a relatively small gear carried by said drive gear and in mesh with said indicating gear, the rotation of said drive gear rotating said driven gear whereby said body portion and said tapering bottom portion of said measuring cup may be moved simultaneously with respect to each other.
2. A device of the type described comprising a tank adapted to hold a liquid, said liquid maintaining a predetermined level in said tank, a liquid valve tube rigidly secured to said tank and having one end extending into said tank to a point above the level of said liquid, the other end of said liquid valve tube being adapted to enter a bottle, a measuring cup disposed concentric with said liquid valve tube in said tank, said measuring cup comprising a cylindrical body portion and a tapering bottom portion, a support, a drive gear, means operatively connecting said cylindrical body portion with said drive gear, a driven gear in mesh with said drive gear, means operatively connecting said bottom portion with said driven gear, an indicating gear carried by said driven gear and rotatable with respect thereto, an indicating point carried by said support and disposed adjacent the peripheral edge of said indicating gear, a relatively small gear carried by said drive gear and in mesh with said indicating gear, and means carried by said support for engaging with said liquid valve tube for preventing any liquid which remains in said tube from passing therethrough while said measuring cup is in the lowermost position.
3. A device of the type described comprising a tank adapted to hold a liquid, said liquid maintaining a predetermined level in said tank, a liquid valve tube rigidly secured to said tank and having one end extending into said tank to a point above the level of said liquid, the other end of said liquid valve tube being adapted to enter a bottle, a measuring cup disposed concentric with said liquid valve tube in said tank, said measuring cup comprising a cylindrical body portion and

a tapering bottom portion, a support, a drive gear, means operatively connecting said cylindrical body portion with said drive gear, a driven gear in mesh with said drive gear, means operatively connecting said bottom portion with said driven gear, an indicating gear carried by said driven gear and rotatable with respect thereto, an indicating point carried by said support and disposed adjacent the peripheral edge of said indicating gear, and a relatively small gear carried by said drive gear and in mesh with said indicating gear, the rotation of said drive gear rotating said driven gear whereby said body portion and said tapering bottom portion of said measuring cup may be moved simultaneously with respect to each other.

70

3. In a device of the type described, a measuring cup comprising a body portion and a bottom portion movably disposed in said body portion, a movable support, a drive gear rotatably carried by said support, a driven gear rotatably carried by said support and in mesh with said drive gear, an adjusting rod having a threaded end receivable in a threaded opening in said driven gear, means carried by the other end of said adjusting rod for holding said bottom portion, a sleeve disposed concentric with said adjusting rod and movable with respect thereto, an arm disposed beneath said support, one end of said sleeve secured to said body portion, the other end of said sleeve secured to said arm, a threaded shank carried by said arm and receivable in a threaded opening in said drive gear, an indicating gear carried by said driven gear and rotatable with respect thereto, an indicating point mounted upon said support and disposed adjacent the peripheral edge of said indicating gear, a relatively small gear carried by said drive gear and in mesh with said indicating gear, and means carried by said support for holding said drive gear and said driven gear against longitudinal displacement, said drive gear being adapted to be rotated for rotating said driven gear, the rotation of said drive gear being adapted to move said shank, said arm, said sleeve and said body portion in one direction, and the rotation of said driven gear being adapted to move said adjusting rod and said bottom portion in the opposite direction simultaneously, said indicating gear having markings thereupon for indicating the capacity of said measuring cup.

4. In a device of the type described, a measuring cup comprising a body portion and a bottom portion movably disposed in said body portion, gears, and gear actuated means operatively connected to said gears for moving said body portion and said bottom portion simultaneously with respect to each other.

5. A device of the type described comprising a measuring cup having a body portion

130

and a bottom portion movably disposed in said body portion, gears, means operatively connected to said gears for moving said body portion and said bottom portion with respect to each other, and gear actuated indicating means for indicating the capacity of said measuring cup.
